OILING GROUPS OF SPINNING TUBES IN FLYER SPINNING AND LIKE FRAMES

Application filed October 19, 1927. Serial No. 227,216.

This invention refers to the spinning tubes which carry the spinning bobbin in flyer spinning and like frames, which tubes are mounted and revolved upon dead spindles, and has for its object the improved working and lubricating of such spinning tubes. According to this invention, groups of spinning tubes which carry the spinning bobbins in flyer spinning and like frames, which tubes are mounted and revolve on dead spindles, are lubricated by means of a supply of oil which when lubrication is required, is raised to such a level as will cause the oil to flow into and lubricate the said tubes. In one case the oil container is placed below the level of the oil tubes. The oil tubes and containers are inverted when lubrication is required and the oil flows into the spinning tube. In another case the oil supply is carried at the same level as the spinning tube. The spinning tube is carried on one limb of a U shaped dead spindle which is tubular throughout. The group of U shaped dead spindles referred to is tilted when lubrication is required so that the oil will overflow at the top of the limb on which the spinning tube revolves and will thus pass into the spinning tube.

Figure 1, is a vertical section through a bobbin and tube constructed in accordance with the invention, and

Fig. 2, is a similar section illustrating another form of the invention.

Fig. 3 is a partial plan view of the embodiment illustrated in Fig. 1, and

Fig. 4 is a partial elevation of the embodiment illustrated in Fig. 1 as seen from the left.

In giving a practical example of our invention as applied to a worsted spinning frame having the flyers mounted and driven on the bottom side of the top rail and the studs and tubes mounted on the same vertical line of axis as the flyer on the lifter rail, we employ Figure 1, a top rail 1 with a flyer 2 mounted and driven in the usual way on the under side of the said rail 1. At a suitable distance below the flyers 2 we mount a lifter rail 3 which is traversed up and down in a usual manner. On the lifter rail 3 we bore

a hole central to the axis of the flyer 2. In a hole in the lifter rail we mount a spindle socket 4 having on its upper side a cup 4¹ and bound on the lifter rail by a cup nut 5. The cup nut 5 acts also as an oil container as hereafter described. We mount firmly in the spindle socket 4 a dead spindle 6 extending upwards to a suitable distance and on it we mount a bobbin tube 7. The cup 4¹ of the spindle socket 4 extends upwards to a suitable distance and has placed on it a cover 8. On the top of the cover 8 a spinning bobbin 9 which is mounted upon the bobbin tube 7 rests. The bobbin tube 7 rests upon a thimble 10 fixed on the dead spindle 6 and resting on the bottom of the cup 4¹ of the spindle socket 4. At the lower end of the bobbin tube 7 we mount clear of the cover 8 of the spindle socket cup 4¹ an inverted oil cup 7¹. The dead spindle 6 extends to the lower end of the spindle socket 4 and has formed on its side an oil groove 6¹ extending upwards into the bobbin tube 7. The cup nut 5 of the spindle socket 4 is made with an oil cup 5¹ at its lower end. This oil cup 5¹ is of sufficient depth to hold a supply of oil. At a suitable distance above the bottom of the oil cup 5¹ of the cup nut we bore an oil hole 5² through which oil is poured into the oil cup 5¹. The lifter rail 3 is invertibly mounted in any known or convenient manner, for instance on trunnions A. When the lifter rail is inverted, the oil cup 5¹ the bobbin tube 7 and dead spindle 6 are inverted, and the oil flows through the groove 6¹ on the dead spindle 6 into the bobbin tube 7 and lubricates same. On being re-inverted any surplus oil flows back to the oil cup 5¹ of the cup nut 5. In other words the oil container is adapted to cause oil to flow into the spinning tube when the lifter rail is turned about the horizontal axis of the trunnions. In giving a second example of our invention also as applied to a worsted spinning frame we employ a top rail, a flyer and a lifter rail all as in the foregoing first example. On the upper side of the lifter rail 3 we mount a stool 11 and in it a U shaped tubular dead spindle 12, the front limb 12¹ of which is coaxial with the flyer 2 and has

mounted on it a bobbin tube 13 carrying a spinning bobbin 14. The back limb 12² of the U shaped dead spindle 12 is filled with oil which passes up into the front limb 12¹, the two limbs rising to the same height. The 5 lifter rail 3 in this form of the invention may also be invertibly, or tiltably mounted, as in the first example described, in any known or convenient manner. It may then be tilted 10 forward to raise the back limbs 12² of a group of dead spindles 12 and lower the front limbs 12¹ so that the oil will overflow into the bobbin tubes and lubricate them.

With the understanding that the examples 15 described and illustrations given are presented, not to limit the invention, but merely to indicate how the invention may be applied,

We claim:

1. Apparatus for lubricating flyer spinning and like frames, comprising a tube for 20 carrying a spinning bobbin, an oil container extending below said tube, and an invertibly mounted lifter rail carrying said tube and said oil container, said oil container being 25 adapted to cause oil to flow into the spinning tube when said lifter rail is turned about a horizontal axis.

2. Apparatus for lubricating flyer spinning and like frames, comprising a tube for 30 carrying the spinning bobbin, an oil container consisting of a U-shaped tubular dead spindle extending below said tube, and an invertibly mounted lifter rail carrying said tube and said oil container, said oil container 35 being adapted to cause oil to flow into the spinning tube when said lifter rail is turned about a horizontal axis.

In testimony whereof we have signed our names to this specification.

40   THOMAS ALEXANDER BOYD.
                 HAROLD ARTHUR BOYD.
                 JAMES BOYD.
